CLAIM

I claim the ornamental design for a vertical post for patio cover, as shown and described.

DESCRIPTION

FIG. 1 is a bottom, front isometric view of a vertical post for patio cover showing my new design;
FIG. 2 is a top, front isometric view thereof;
FIG. 3 is a front elevation view thereof;
FIG. 4 is a left side elevation view thereof; and,
FIG. 5 is a top plan view thereof.

1 Claim, 5 Drawing Sheets
